UNITED STATES PATENT OFFICE.

FREDERICK WILLIAMS, OF SOMERVILLE, MASSACHUSETTS, ASSIGNOR TO ACME REGISTER COMPANY, OF SOMERVILLE, MASSACHUSETTS, A CORPORATION OF MASSACHUSETTS.

CIRCUIT-CLOSER.

1,143,676.

Specification of Letters Patent. Patented June 22, 1915.

Application filed May 10, 1913. Serial No. 766,711.

To all whom it may concern:

Be it known that I, FREDERICK WILLIAMS, of Somerville, in the county of Middlesex and State of Massachusetts, a citizen of the 5 United States, have invented a new and useful Improvement in Circuit-Closers, of which the following is a specification.

My invention is an improvement upon the form of electrical recorder customarily used 10 by employers to register the time of beginning and leaving off work, and it is of a type in which each workman has his own key by which a circuit is closed momentarily and a record thereby made upon a dial 15 or tape.

This invention relates to the circuit closer which is individual, each employee having his own instrument operated by his own key, and it will be understood by reference to the 20 drawings, in which—

Figure 1 is a plan of a device embodying my invention, the casing being removed. Figs. 2 and 3 are respectively side and end elevations of a key adapted to be used with 25 my circuit closer. Fig. 4 is a plan, the key-centering housing being removed, the key being shown in section and in locked position. Fig. 5 is a similar view in which the key is shown closing one of the circuits. 30 Fig. 6 is a similar view showing the key closing the other circuit. Fig. 7 is a side elevation, the casing being in section, and Fig. 8 a section on line 8—8 of Fig. 1, the key being in place and in condition to be 35 turned.

A is a base made of insulating material on which are mounted two terminals B and C each in close proximity to an arm d , d' which arms form a forked terminal D. The 40 arms d , d' are spring or yielding arms as are also the terminals B and C. The terminals B and C form parts of plates B^1 and C^1 , which are mounted on the base A. The terminal D is attached to a housing E also 45 mounted on the base A and slotted as at e to receive the key F.

On the under side of the housing E is a stop e^1 to prevent the key from being turned in the wrong direction, and on the base A is 50 mounted a stud a carrying a projecting arm a^1 or ward with which slots f in the key must register. The position of the arm differs in the different circuit closers and more than one arm may be used, thus preventing

any key but the one intended from being 55 used in a particular circuit closer. A socket A¹ in the base receives the end of the key and serves to center it. In addition there is preferably provided a spring rod which will prevent the key from being turned or withdrawn unless the rod is first withdrawn. This mechanism as shown comprises a guide piece G attached to the base A and having two uprights g , g^1 having openings in which slides the rod H. The rod H has a collar h 60 held against a pin h^1 by a spring h^2 , the other end of the spring resting against the upright g so as to hold the rod H in its forward position, the upright g^1 serving with the pin h^1 as a stop to control the in- 70 ward movement of the rod. The front end of the rod H has a jaw as at h^3 to straddle one of the wings f^1 , f^2 of the key F. The other end of the rod has a knob or other convenient handle H¹ by which it may be withdrawn to release the key so that it may be 75 turned, and to allow the key after it has been turned to resume a fore and aft position so that it may be withdrawn.

The wings f^1 , f^2 of the key differ slightly 80 in what may be termed their radial length, one of them f^1 extending slightly farther from the axis of the key than the other. This wing may be termed the active or operating wing which engages either the arm 85 d or the arm d' to press it against its opposing terminal to close the circuit. The other wing f^2 might be termed a stop wing in that its function is to engage the stop d^1 and so prevent the key from being turned in the 90 wrong direction. The manner in which the wing f^1 operates is indicated in Figs. 5 and 6. In Fig. 5 the wing f^1 is causing the engagement of the arm d^1 with the terminal C. In order to accomplish this end, the key is 95 inserted in the keyhole with the wing f^1 in engagement with the jaw h^3 which registers with a portion of the keyhole in the casing K. When the rod H is withdrawn so that the key may be turned, the stop e^1 prevents 100 the key from being turned anti-clockwise. In turning it clockwise it is brought into the position shown in Fig. 5 where it has made the principal contact and the wing f^2 has come into contact with the stop e^1 , to prevent the key from being rotated farther.

To bring the key into the position shown in Fig. 6, where it has caused the contact

2
between the arm d and the terminal B, the key is reversed in the keyhole and upon withdrawing the rod H the key is again turned clockwise. The wing f^2 in this case, 5 because of its engagement with the stop e^1 , prevents the turning in the wrong direction and at the same time is not sufficiently long to cause the engagement or contact of the arm d^1 with the terminal C. By reason of 10 the directions on the end of the key, as shown in Fig. 3, the operator knows which way to insert his key in order to make the proper record at the central station or office.

This circuit closer may be put at any 15 convenient point and in practice each employee has his own circuit closer which may be attached to his bench, his desk or any convenient place near his work. It is wired as indicated, the wire j running to the "in" 20 register and the wire j^1 running to the "out" register which may be in the same station. j^2 is the wire which completes both circuits.

The employee on reaching his instrument 25 inserts his key into the instrument in the position shown in Fig. 3 i. e. so that the word "in" is right side up. Holding back the rod H he gives the key a turn until the wing f^1 brings up against the stop e^1 . 30 During its travel the wing f^1 will engage say the arm d and close the circuit through the terminal B. After this he withdraws the key. This, however, he cannot do without bringing the key into register with the opening or slot e and hence without withdrawing the rod as before. Thus it takes both hands 35 of the employee to close the circuit and make the register at the central station. When the employee leaves his work he repeats the 40 above operation except that he reverses the position of the key so that the wing f^2 will close the circuit closer through the terminal C pushing it against the arm d^1 .

A casing K preferably covers the mechanism, being provided with an opening K^1 45 through which the key F may be inserted and a second opening K^2 through which the rod H projects. It is attached to the base A by screws k or in any other convenient way. 50 The details of construction of this device may be varied without departing from the spirit of this invention, which involves the two sets of terminals, each set capable of being brought into contact by its own portion of the key and the use of wards to

which the shape of the key must conform, thus insuring the use of the right key.

What I claim as my invention is:—

1. A device of the kind described comprising an insulating base, a forked terminal mounted thereon, two terminals each located in proximity to one of the arms of said forked terminal, and means whereby either one of the arms of said forked terminal may be brought into contact with the adjacent terminal, said means comprising a key having wings of different lengths, the longer wing of said key being adapted to engage said terminals, in combination with a stop adapted to engage the shorter wing and limit the direction and extent of rotation of the key. 65

2. In a device of the kind described, in combination, an insulating base, a forked terminal mounted thereon, two terminals each located in proximity to one of the arms of said forked terminal, a key adapted to be located between the ends of said forked terminal and having wings of different lengths, said wings having slots, a ward 80 adapted to coöperate with said slots, and a stop adapted to engage said key to limit its path of rotation. 75

3. A device of the kind described comprising an insulating base, a forked terminal mounted thereon, two terminals, one located in proximity to each of the arms of said forked terminal, a casing mounted on said base and covering said terminals, a keyhole in said casing, and a spring-controlled rod provided with a jaw at the inner end thereof mounted to slide into and out from said casing and normally registering with the walls of said key-hole to receive a terminal-engaging key and prevent its operation. 90

4. In a device of the kind described, in combination, an insulating base, a forked terminal mounted thereon, two terminals each located in proximity to one of the arms of said forked terminal, a key adapted to be located between the ends of said forked terminal and having wings of different lengths, and means whereby when said key is in rotary action it will be prevented from being turned into withdrawing position. 100

FREDERICK WILLIAMS.
